MULTIPLIER UNIT AND SUPPORTING MEANS

Stanley V. Forgue, Cranbury, N. J., assignor to
Radio Corporation of America, a corporation of
Delaware

Application February 7, 1946, Serial No. 646,075

6 Claims. (Cl. 250—175)

1

This invention relates to multiplier units for television pick-up tubes such as disclosed, for example, in the application of Paul K. Weimer, filed September 16, 1944, Serial No. 554,494, now U. S. Patent 2,433,941, issued January 6, 1948, and means for supporting the units within the tube as a rigid assembly to and around the cathode gun.

It is an object of the invention to mount the parts of a multiplier unit together by stamped sheet metal parts.

Another object of the invention is to mount a delicate fine mesh screen in taut condition within a supporting frame.

Another object is to mount the multiplier units and cooperating electrodes securely within the tube.

Other objects of the invention will appear in the following description, reference being had to the drawings, in which:

Fig. 1 is an elevation of the spacing wheel used in the multiplier unit.

Fig. 2 is an elevation of the clamping ring.

Fig. 3 is a section taken on the line 3—3 of Fig. 2.

Fig. 4 is an elevation of the bushing.

Fig. 5 is an elevation of the pinwheel dynode of the multiplier unit, only a few of the blades being shown to simplify the illustration.

Fig. 6 is an edge view of the pinwheel, two blades, only, being shown, the others being omitted to simplify the illustration.

Fig. 7 is a sectional elevation of the assembled parts of the multiplier unit taken on a diameter of the circular parts.

Fig. 8 is an elevation of the multiplier disc constituting the final dynode of the series of multipliers.

Fig. 9 is a sectional elevation of the assembled parts of the final multiplier stage, taken on a diameter of the circular parts.

Fig. 10 is an elevation of multiplier units assembled on the gun of a cathode ray tube illustrating the method of mounting in relation to the gun and other parts of the tube.

Referring to Figs. 5 and 6 of the drawing, the "pinwheel" dynode 1 is particularly disclosed in said application of Paul K. Weimer and need not be disclosed in complete detail herein, as it is not claimed and is not part of this invention except for the manner of mounting the parts. It may be said, however, that the pinwheel is stamped from a thin sheet of silver-magnesium and is circular in form with a plurality of vanes 2 stamped out at about 35° therefrom. In appear-

ance it is somewhat similar to an electric fan. When a series of these units is used in a tube, as in Fig. 10, one pinwheel has blades extending to the right, as in Fig. 6, and the next unit has 5 a pinwheel with the blades extending to the left, and so on. The electrons strike against these blades when used in a cathode ray tube to produce secondary emission, the electrons of which are attracted toward and impinge against the next dynode. The thin sheet metal from which the dynode is made is clamped at its periphery around a circular Nichrome ring 3 and at its center part the metal is stamped to provide a small circular hub 4 having a bore to fit in spaced 10 insulated relation over the gun, generally indicated at 5 in Fig. 10. In this gun, 6 indicates the first anode having an end surface 7 constituting the first dynode of the multiplier. The grid is indicated at 8 and the cathode at 9. Certain parts are broken away to show these electrodes.

A wheel 10 is stamped from thin sheet Nichrome (Fig. 1) with a minimum number of spokes 11 between the inwardly extending flange 11' of the outer rim 12 and the outwardly extending flange 12' of hub 13 (see also Fig. 7). A fine screen 14 of circular form with a diameter in excess of the diameter of the spoked wheel 10 is adapted to be clamped between the flange 11' and the rim 12 of the wheel by the flange 15 and the band 16 of ring 16', as shown in Fig. 7. Tabs 17 on the rim 16 are adapted to be turned against the pinwheel when the other parts are assembled therein. The screen shields the dynode blades 2 from preceding potentials while permitting most of the electrons to pass through the meshes to bombard the pinwheel blades 2 with minimum hitting of the fine strands of the screen. In some cases it is desirable to turn these spokes 20 90°, so that they will be edgewise to the electron stream. The screen 14 also has a central opening of smaller diameter than the opening in hub 13 of the spoked wheel. A flanged bushing 18 of thin Nichrome metal has an outside diameter 25 differing from the inside diameter of the hub 13 by about twice the thickness of the thin screen 14.

In assembling the parts as illustrated in Fig. 7, the rim 16 is pressed over the spoked wheel 10 so that the periphery of the screen is bent and wedged therebetween. The bushing 18 is placed 30 so as to clamp the inner edge of the screen 14 against the hub 13 of the spoked wheel 10. If desired, the rim 16 and rim 12 of wheel 10 may 35 be spot welded together through the screen and

the hub 13 and bushing 18 may be similarly spot welded. The pinwheel 1, with the blades extending inwardly of the assembly, is placed in position so that its bead fits inside the rim 16 and against the edge of rim 12 and its hub 4 fits inside the bushing 18. When the parts are in this position, as shown in Fig. 7, the tabs 17 are bent inwardly against the pinwheel 1. The parts of the multiplier unit are then held firmly in assembled position.

The final or fifth dynode, as shown is not of the pinwheel type. It consists of a circular silver-magnesium disc 19, the periphery of which is wrapped around a Nichrome ring 20. This disc has a central hole to fit over the gun when in assembled position. The dynode disc is placed inside the rim 16 of the ring 15 (Figs. 2 and 9) and a retainer ring 21, like the wheel of Fig. 1 except the spokes are omitted, is abutted against the bead of the disc 19. The tabs 17 are then bent down against this ring to hold the parts together.

The collector electrode consists of a fine mesh screen like the shield screen of 14. This electrode, when mounted, is exactly like the assembly shown in Fig. 7 with the pinwheel removed. The tabs 17 are then bent down against the rim of spoked wheel 10.

The fifth multiplier stage 22, the collector stage 23, the fourth multiplier stage 24, the third multiplier stage 25 and the second multiplier stage 26 are assembled over the gun 5 in the order mentioned before the end 7, which is the first multiplier stage, is mounted in the first anode cylinder 6, as disclosed in my co-pending application, filed January 28, 1946, Serial No. 643,925, now U. S. Patent 2,441,315 issued May 11, 1948. Alternate ones of the pinwheel dynodes have the blades bent in opposite directions to better intercept the electrons, as already explained.

The multiplier units are supported on a plurality of ceramic tubes 27 in which are conducting wires 28 for supplying potential to various electrodes. The units are fastened to the tubes by U-shaped straps 29, welded to the rims 16. These are bent around the tubes and the ends welded together. These tubes support the cylindrical base 30 by means of U-shaped straps 31. The gun 5 is assembled and mounted on the base 30, as disclosed in my said application.

A potential ring 32, commonly called a "persuader," is also mounted on the insulation tubes 27 by straps 29. A potential cylinder 33 is also secured to the tubes by means of U-shaped straps 34. This cylinder has the function of and displaces the usual wall coating. Other electrodes, such as the target, decelerator and photocathode ring, shown in said Weimer application, may be supported on the tubes 27, shown broken off at the right in Fig. 10. The wires 28 are also shown broken off at the left of Fig. 1. They are to be welded to lead-in rods at the base of the tube. This is not part of my invention and is not shown.

Spring snubbers 35 are welded to the wires 28, as at 36, or to the electrodes, as at 37, and the free ends extend in arcuate position, so that when the complete unit is assembled inside the tube these snubbers will contact with the glass envelope to resiliently support one end of the complete assembly inside the tube, the other end being supported by the lead-in rods.

The connectors for supplying potentials to the various dynodes and other electrodes are not

shown, as connections may be made in well-known ways.

The number of multiplier dynodes has been given by way of example, only. More or fewer 5 multiplier stages, of course, may be used and various other changes made without departing from the scope of the invention.

The operation of the multiplier is described fully in said Weimer application, but it may be 10 said briefly that the beam electrons returning from the vicinity of the target strike the surface of the first dynode 7 and bombard secondary electrons therefrom. These are directed by persuader 32 into the second multiplier stage 26, where they hit the surface of the pinwheel blades 2 and bombard secondary electrons therefrom. The screen 14 of Fig. 7 permits the primary electrons to pass through to engage the blades, but it screens the secondary electrons 15 from preceding potentials and these are attracted through the spaces between the blades 20 to the shield screen of the next multiplier stage, where they bombard secondary electrons from the blades therein. This continues until the secondary electrons bombarded from the 25 final stage 22 are attracted to the screen collector stage 23 and the current passes therefrom to the output terminal of the tube (not shown).

I claim:

30 1. A multiplier unit for television transmitter tubes comprising a metal wheel having an outer rim with an inwardly extending flange, a hub with a bore and an outwardly extending flange and spokes connecting said flanges together, a fine mesh metal screen having an opening adjacent said bore, a ring having a band and an inwardly extending flange pressing said screen against said rim and the first-mentioned flange, and a bushing in said bore having an outwardly 35 extending flange, said bushing pressing said screen against the circumferential wall of said bore and the flange of said hub, a portion of said ring being bent inwardly for holding said wheel and screen together therein.

40 2. A multiplier unit for television transmitter tubes comprising a metal wheel having an outer rim with an inwardly extending flange, a hub with a bore and an outwardly extending flange and spokes connecting said flanges together, a fine mesh metal screen having an opening adjacent said bore, a ring having a band and an inwardly extending flange pressing the outer edge of said screen against said rim and the first-mentioned flange, a bushing in said bore having an outwardly extending flange, said bushing pressing the inner edge of said screen against the flange of said hub, and a multiplier dynode having an outer rim seated within said first-mentioned rim, a portion of said ring being bent inwardly for holding said wheel, screen and dynode together therein against the inwardly extending flange.

45 3. A multiplier unit for television transmitter tubes comprising a metal wheel having an outer rim with an inwardly extending flange, a hub with a bore and an outwardly extending flange and spokes connecting said flanges together, a fine mesh metal screen having an opening adjacent said bore, a ring having a band and an inwardly extending flange pressing the outer edge of said screen against said rim and the first-mentioned flange, a bushing in said bore having an outwardly extending flange, said bushing pressing the inner edge of said screen against the circumferential wall of said bore and the flange

of said hub, and a multiplier dynode having an outer rim seated within the rim of said wheel and a hub extending into said bushing, a portion of said ring being bent inwardly for holding said wheel, screen and dynode together therein against its inwardly extending flange.

4. A multiplier unit for television transmitter tubes comprising a metal wheel having an outer rim with an inwardly extending flange, a hub with a bore and an outwardly extending flange and spokes connecting said flanges together, a fine mesh metal screen having an opening adjacent said bore, a ring having a band and an inwardly extending flange pressing the outer edge of said screen against said rim and the first-mentioned flange, a bushing in said bore having an outwardly extending flange, said bushing pressing the inner edge of said screen against the circumferential wall of said bore and the flange of said hub, a multiplier dynode having an outer rim seated within the rim of said wheel and a hub extending into said bushing, and tabs on said ring for holding said wheel, screen and dynode together therein against the inwardly extending flange.

5. A multiplier unit for television transmitter tubes comprising a metal wheel having a peripheral member, a hub with a bore and spokes connecting said hub and member together, a fine

mesh metal screen having an opening adjacent said bore, a ring pressing said screen against said peripheral member, and a bushing in said bore pressing said screen against the hub to hold said wheel and screen together.

6. A multiplier unit for television transmitter tubes comprising a metal wheel having a peripheral member, a hub with a bore and spokes connecting said hub and member together, a fine mesh metal screen having an opening adjacent said bore, a ring pressing said screen against said peripheral member, a bushing in said bore pressing said screen against said hub, and a multiplier dynode having an outer rim seated within said first-mentioned rim, said member clamping said wheel screen and dynode together.
